UNITED STATES PATENT OFFICE.

FREEMAN R. WILLSON, JR., OF WORTHINGTON, OHIO, ASSIGNOR, BY MESNE ASSIGNMENTS, TO THE JEFFREY MANUFACTURING COMPANY, A CORPORATION OF OHIO.

CONVEYER.

977,987.

Specification of Letters Patent.

Patented Dec. 6, 1910.

Application filed August 3, 1905. Serial No. 272,597.

To all whom it may concern:

Be it known that I, FREEMAN R. WILLSON, JR., a citizen of the United States, residing at Worthington, in the county of Franklin and State of Ohio, have invented certain new and useful Improvements in Conveyers, of which the following is a specification, reference being had therein to the accompanying drawing.

10 My invention relates to that class of conveyers in which idler pulleys or rollers are employed for giving to a conveyer belt a trough-like form for the purpose of retaining the material laterally.

15 The object of my invention is to provide improved means for supporting adjustably the idler pulleys of such a conveyer.

Figure 1 of the drawings is a side elevation of an embodiment of my invention. 20 Fig. 2 is a cross-sectional view taken on the line 2—2 of Fig. 1. Fig. 3 is an elevation of the structure shown in Fig. 1, as seen looking in the direction of the arrow of said figure.

25 In the drawings, *a* indicates a cross brace to which is secured by means of the bolts *a'* the base frame *A* upon which some of the pulleys are supported. This base frame *A* consists of two vertical walls *B*, *C* and the 30 central relatively horizontal web plate *Q*, the two vertical walls and the web being cast integrally with each other. The central web plate *Q* presents a contour in transverse vertical planes of a peculiar form, having a purpose to be presently described.

35 *D* indicates a centrally disposed horizontal pulley suitably mounted upon pedestals independent of the base frame *A*, already described, although it will be readily understood that such independent mounting is not a necessary feature of a construction embodying my invention.

40 *E*, *E'* are side pulleys which are inclined to the horizontal and are disposed symmetrically on either side of the central pulley *D*, the whole being arranged to support a conveyer belt *F* in trough-shape. The pulley *D* is shown as offset from the vertical plane of the two pulleys *E*, but some of the 45 aspects of my invention are such that this offset feature of the central pulley is not requisite to an embodiment of the invention.

50 Each side inclined pulley *E* is carried by

a bracket or frame *G* longitudinally disposed relatively to the pulley, the said 55 bracket or frame being provided with upwardly extending arms *H*, *H'*, which afford bearings in which the pulley-shaft *e* is journaled at either end. The more outwardly disposed arm *H'* has a lateral extension or 60 projecting portion *I*, in which is keyed or bolted a shaft *i* adapted to carry the guide idler pulley *J*, the latter serving to guide the conveyer belt and to keep either edge thereof from slipping or jumping upwardly 65 to an undesirable extent.

The frame *G* carrying the pulley *E* is of a width suitable to fit in between the walls *B*, *C*, of the lower stationary frame, and its lower portion moves more or less freely between the parts *B*, *C*, in a longitudinal direction. The said frame *G* in section somewhat resembles an I-beam, having a relatively narrow web portion *g* with upper and lower flanges *g'*, *g''*, and is provided with a 70 curvilinear slot *K*, preferably cut in the arc of a circle. Passing through the vertical walls *B*, *C*, of the lower stationary frame, and through the slot *K*, is a pin *L*, preferably screw-threaded.

75 The inner end of the frame *G* is curved at its lower edge, the curve being in the form of an arc of a circle, the center of which is at the point indicated by the letter *R* on the drawings. The slot *K* is likewise in the form of an arc of a circle about the same center. The web *Q* presents in longitudinal sectional outline a double curve made up of the arcs of circles whose centers are at the points *R*, *R'* respectively. The 80 side pulleys *E* can be adjusted by moving the frame *G* to any desired position with respect to the base frame *A*. During such movement of adjustment the curved end of the frame *G* engages the web plate *Q* which 85 thus becomes a bearing surface. The frame *G* is held in position against the web *Q* by means of the slot *K* and pin *L*, already described.

90 When a predetermined adjustment of the frame *G* on the pin *L* is obtained, the frame is locked in the desired position by means of a hand-wheel *M* movable on the exterior screw thread of the pin *L*. The said hand-wheel is provided with an elongated hub- 95 portion *m* which passes through a hole in

the side wall B and abuts tightly against the web portion of the adjustment frame G as the hand wheel is turned the proper distance.

5 The manner of operation of the pulley support, above described, and the advantages of its construction will be readily apparent. The overlap of each of the side pulleys with respect to the central pulley is
10 constant for all positions of angular adjustment of the former. The distance between the pulleys J—J along the upper contact edges of the three pulleys E, F, E is constant for all positions of adjustment of the
15 pulleys E, E. As a result of this constant distance between the edge guide pulleys J—J, the belt is prevented from being lashed back and forth transversely, a fault which results in prior constructions from
20 pivoting the pulleys at relatively low points and is apparent when the side pulleys are adjusted to their lowermost positions.

By forming the slot K, the lower edge of the frame G and the web plate Q with
25 curved surfaces concentric with a point upon the upper belt contacting edge of the pulley, the pulley is maintained in constant relation with the belt transversely in all positions of adjustment. Other advantages
30 also result from the construction described,

which will be readily apparent, and which I do not consider it necessary to describe in detail.

What I claim is:—

1. A conveyer belt support comprising a 35 horizontal central pulley, a stationary support having two curved surfaces each presenting in vertical section an arc of a circle about one end of the upper contacting edge of the stationary pulley as a center, two pulley carrying frames, each formed at its inner end with a mating curved surface adapted to rest upon and slide over one of the said curved surfaces upon the support, and pulleys carried by said pulley carrying frames 40 and supported at a variable angle of inclination at the two ends of the horizontal pulley to form a three pulley troughing belt support.

2. A conveyer belt support comprising a 50 central horizontal pulley, side inclined pulleys, adjustable frames for the latter having curved inner and lower edges, and a double arched seat therefor.

In testimony whereof I affix my signature, 55 in presence of two witnesses.
